(57) **CLAIM**

The ornamental design for a quadcopter, as shown and described.

DESCRIPTION

FIG. 1 is an isometric view of a quadcopter in an unfolded configuration of use, the isometric view being from the front, left side, and top;

FIG. 2 is an orthogonal front view of the quadcopter of FIG. 1 in an unfolded configuration;

FIG. 3 is an orthogonal back view of the quadcopter of FIG. 1 in an unfolded configuration;

FIG. 4 is an orthogonal right side view of the quadcopter of FIG. 1 in an unfolded configuration;

FIG. 5 is an orthogonal left side view of the quadcopter of FIG. 1 in an unfolded configuration;

FIG. 6 is an orthogonal top view of the quadcopter of FIG. 1 in an unfolded configuration;

FIG. 7 is an orthogonal bottom view of the quadcopter of FIG. 1 in an unfolded configuration;

FIG. 8 is an isometric view of the quadcopter shown in FIG. 1 in a folded configuration of use, the isometric view being from the front, left side, and top;

FIG. 9 is an orthogonal front view of the quadcopter of FIG. 8 in a folded configuration;

FIG. 10 is an orthogonal back view of the quadcopter of FIG. 8 in the folded configuration;

FIG. 11 is an orthogonal right side view of the quadcopter of FIG. 8 in the folded configuration;

FIG. 12 is an orthogonal left side view of the quadcopter of FIG. 8 in the folded configuration;

FIG. 13 is an orthogonal top view of the quadcopter of FIG. 8 in the folded configuration; and,

FIG. 14 is an orthogonal bottom view of the quadcopter of FIG. 8 in the folded configuration.
